UNITED STATES PATENT OFFICE.

WILLIAM FIELDHOUSE, JR., OF PATERSON, NEW JERSEY.

SHADE-ROLLER BRACKET.

SPECIFICATION forming part of Letters Patent No. 727,333, dated May 5, 1903.

Application filed October 14, 1902. Serial No. 127,208. (No model.)

To all whom it may concern:

Be it known that I, WILLIAM FIELDHOUSE, Jr., a citizen of the United States, residing in Paterson, in the county of Passaic and State 5 of New Jersey, have invented certain new and useful Improvements in Shade-Roller Brackets; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 This invention relates to shade-roller brackets or fixtures of the class in which the bracket proper—that is to say, the part which directly supports the shade-roller—is arranged for lateral adjustment, so that various lengths 20 of shade-rollers may be accommodated.

The object of the invention is to provide a device of this nature which shall embody as its principal characteristics simplicity and facility of adjustment.

25 The invention will be found fully illustrated in the accompanying drawings, wherein—

Figure 1 is a perspective view of the device. Fig. 2 is a view showing the device partly in side elevation and partly in vertical 30 section. Fig. 3 is an underneath view of the adjustable member of the device. Fig. 4 is a view, partly in plan and partly in horizontal section, of said adjustable member; and Fig. 5 is a view in side elevation of a modified form of the invention.

35 Simplicity being one of the principal objects of the invention, the device consists of two members *a* *b*, each cast in a single piece, the member *a* being a support for the member *b* 40 and consisting of a plain strip of metal whose cross-section is preferably dovetailed, as at *c*, while the member *b* is in the form of a relatively short stout arm having its mounting portion relatively widened, as at *d*, and formed 45 with a transverse groove *e* across its end, which is shaped to correspond to the cross-sectional shape of the member *a*. The member *a* is adapted to be secured to the window-casing by screws or the like, for the reception 50 of which holes *f* are formed in the ends of the strip of which said member is composed. Extending lengthwise of the groove *e* there is formed in the end of the arm of the member *b* a depression *g*, the end walls of

which are recessed, as at *h*. In this depression seats a bent plate-spring *i*, whose ends take in the recesses *h*, whereby it is thus held in place in the member *b*. The plate-spring projects somewhat beyond the bottom of the groove *e*, so that when the member *b* is slid 60 upon the member *a* said plate-spring bears against the surface of the member *a*, and thus acts to hold member *b* securely at any point on member *a* to which it is adjusted.

Of course if the parts are made to snugly 65 fit each other the securing of the members together at any point to which the member *b* may be adjusted will be sufficiently stable for all practical purposes although the plate-spring should be omitted. I therefore do not 70 wish to be limited to a combination in which the plate-spring shall be included as an element.

It will be understood that the device is used in pairs, the member *b* of one being formed 75 with the usual round opening for the round trunnion of the shade-roller, while the member *b* of the other has the square opening for the square trunnion of the roller.

If it is desired to employ the device for the 80 support of a curtain-pole, the member *b* may be formed with an extension *j*, formed with a recess *k*, for this purpose.

Having thus fully described my invention, what I claim as new, and desire to secure by 85 Letters Patent, is—

The combination of two members, one of which consists of an elongated part and the other of which has an interlocked sliding engagement with said first-named member and 90 is formed with a groove receiving said first-named member and a depression in the bottom of said groove extending longitudinally thereof, said depression having its ends formed as recesses, and a spring disposed in 95 said groove between said members and having its ends projecting into the recesses of said depression and its middle portion projecting out of said depression and engaging said first-named member, substantially as described.

In testimony that I claim the foregoing I have hereunto set my hand this 11th day of October, 1902.

WILLIAM FIELDHOUSE, JR.
